UNITED STATES PATENT OFFICE.

HERBERT W. CHENEY, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

MOTOR-CONTROLLING MECHANISM.

No. 875,981.

Specification of Letters Patent.

Patented Jan. 7, 1908.

Application filed June 8, 1906. Serial No. 320,757.

To all whom it may concern:

Be it known that I, HERBERT W. CHENEY, citizen of the United States, residing at Norwood, in the county of Hamilton and State of Ohio, have invented certain new and useful Improvements in Motor-Controlling Mechanism, of which the following is a full, clear, and exact specification.

My invention relates to starters for electric motors, and more particularly to resistance starters for induction motors.

Heretofore induction motors have been made with a starting resistance within the rotor, in order to avoid the rubbing contact between the collecting brushes and the slip-rings when the motor is running normally. This involves a very complicated and bulky structure of the rotor. It has also been proposed to have the starting resistance external to the rotor and connected thereto by slip-rings. This allows the rotor to be simplified in structure and diminished in size, but has the disadvantage of a permanent sliding contact at the slip-rings.

One of the objects of my invention is to provide means whereby the starting resistance may be outside of the rotor, but the final short-circuit may take place within the rotor. By this I am enabled to avoid the disadvantages due on the one hand to the increase in size and complication of the rotor when the resistance is internal, and on the other hand those due to the sliding contact at the slip-rings after the motor has been started.

Another object of my invention is to provide certain electrical interlocks for preventing the starting of the motor when any of the controlling devices are in improper position for such starting.

A further object of my invention is to provide a novel form of rheostat and actuating mechanism therefor.

A still further object of my invention is to permit a remote control of the short-circuiting device.

In one of its aspects my invention comprises an induction motor, an external resistance in the secondary circuit thereof, and means within the motor for short-circuiting said resistance.

More specifically my invention comprises

the combination with an induction motor, of a rheostat in the rotor circuit thereof, means which in one position short-circuits the rotor windings internally, and electromagnetic means for automatically moving said short-circuiting means into operative position when the rheostat is moved into its position of lowest resistance, and for automatically opening said short-circuit when the rheostat is moved out of such position.

In another aspect my invention comprises an induction motor, a magnetically operated, switch for admitting current thereto, a starting resistance arranged to be included in the rotor circuit of the motor, and connections whereby the operating magnet of the current-admitting switch can be energized only when the starting resistance is fully in circuit.

In still another aspect my invention comprises, in an induction motor, a rotor having its windings connected to slip-rings, and power-operated means for short-circuiting said slip-rings.

In a more specific aspect, my invention comprises in an induction motor, a rotor having its windings connected to slip-rings, electrically-operated means for short-circuiting said slip-rings, and a master controller for said electrically operated means.

From another point of view, my invention comprises a drum controller and a rectilinear-slide rheostat mechanically connected to operate together; or more specifically, the combination of an induction motor, a magnetically operated switch for admitting current to the primary element thereof, a rectilinear-slide rheostat connected to the secondary element of said motor, a drum controller, a single operating device mechanically connected to the rheostat and drum controller to impart movement thereto, and electrical connections for the drum whereby the operating magnet of the current-admitting switch can be energized only when the rheostat is in position of highest resistance.

From still another point of view my invention comprises a rheostat having its contact surfaces downward and immersed in oil; or more specifically, the combination, in a controlling device, of a series of contacts having their contact surfaces downward, a carriage carrying contact fingers which are upwardly

2
spring-pressed into sliding engagement with said contact surfaces, and arranged to connect different contact surfaces together to vary the resistance of the rheostat, and a movable tank of oil in which the carriage, contact fingers and contact surfaces are immersed.

Other features of my invention will appear from the following description in connection with the accompanying drawings, and will be specifically pointed out in the claims.

Figure 1 is a partly diagrammatic view, showing my invention in connection with a rectilinear-slide starting rheostat. Fig. 2 is an elevation showing the structure of a rectilinear-slide starting rheostat arranged to be operated by a rotary drum controller. Fig. 3 is a longitudinal section through the drum controller. Fig. 4 shows a development of 20 the drum with the circuits controlled thereby. Fig. 5 is a section on the line 5—5 of Fig. 2, with some of the parts partially sectioned on other lines to better show the construction. Fig. 6 is a section on the line 6—6 of 25 Fig. 2. Fig. 7 is a sectional view of one of the operating magnets of the short-circuiting device.

In the drawings A is an alternating current motor, here shown as a rotor-wound 30 induction motor, which is supplied with current by the mains 1, 2 and 3, through the switch 4. This switch is biased toward "off" position by spring 5, but may be moved into "on" position by solenoid 6, in which latter 35 position it is held by latch 7 until such time as the latch is released by the energization of the solenoid 8. The circuit of this solenoid 8 may be closed either by a push button 9, or by an overload magnet 10 which is connected to the secondary of a series transformer 11, the primary of which is in the main 3. The secondary or rotor circuit of motor A is connected through the slip-rings 12 to a stationary starting rheostat or variable resistance 13 having contacts 40. This 45 resistance is composed of three parts, here shown as star connected to correspond with the connections of the rotor windings. This resistance may be delta-connected if the 50 rotor windings are so connected, the two generally corresponding. This resistance can be varied by means of a sliding bar 14, movable, by a handle 14', over the contacts 40.

Within the slip-rings of the rotor is a 55 power-operated device 15 for internally short-circuiting the rotor windings. This device may be of any desired construction, but should be, as shown, so arranged that it can rotate with the slip-rings. This device 60 is movable along the shaft of the motor A, and in its inner position connects or bridges the slip-rings 12 to internally short-circuit the rotor windings by simultaneously engaging the inward projections 16 from said 65 rings. In its outer position the device 15 is

out of engagement with the projections 16 and the internal short-circuit of the rotor is broken. This short-circuiting device is movable into and out of short-circuiting position by magnets 17 and 18 respectively, energized 70 by a battery or other source of current 19 and under the remote control of the master controller. The structure of these magnets will be hereinafter explained. The circuits of the magnets 17 and 18 are closed during 75 the movement of the resistance-varying bar or master controller 14 by an extension 20 therefrom. As the bar 14 is moved between the position of highest resistance and the next position thereto, or between the position of lowest resistance and the next position thereto, the circuit of magnet 18 is completed by extension 20, to cause it to move the device 15 out of short-circuiting position should it be in such position. As the resistance-varying bar 14 is moved into its position of lowest resistance, the circuit of magnet 17 is completed by extension 20, to cause it to move the device 15 into its short-circuiting or bridging position. As the short-circuiting device is moved into this position, such movement breaks the circuit of magnet 17 at the switch 21. This remote control of the short-circuiting device is believed to be broadly new with me. 95

The solenoids 6 and 8 are supplied by the battery 22 which is here shown as being distinct from the battery 19. It is obvious, however, that if the magnets 6, 8, 17 and 18 are wound for the same voltage, a common 100 source of supply may be used for all of said magnets, as shown diagrammatically in Fig. 4. In order to complete the circuit of solenoid 6, it is necessary that the resistance varying bar 14 be in position 0, i. e., its 105 position of highest resistance, and that the short-circuiting device 15 be out of its bridging position, thus closing the switch 23. If such is the condition, the circuit of the magnet 6 may be closed by the push button 110 24. If such is not the condition, it is impossible to close the main switch 4, and therefore current cannot be supplied to the primary member of motor A unless all of the resistance 13 is included in the secondary 115 circuit thereof by reason of the bar 14 being in its highest resistance position and the internal short-circuit of the rotor winding being open.

The operation of the system above described is as follows: With the parts in the position shown, the current-admitting switch 4 can be closed by pressing the button 24. As the motor A begins to increase in speed 120 the master controller, consisting of the resistance varying bar 14, is moved by handle 14' out of the position in which it is shown toward the right, thereby gradually cutting the resistance 13 out of the rotor circuit of said motor. As the resistance-varying bar 130

is moved in this direction, the magnet 18 is energized twice *i. e.*, as bar 14 passes from positions 0 to 1, and from 7 to 8, but does nothing at this time, because the short-circuiting device 15 is already in open position. When the bar 14 reaches its eighth or lowest resistance position, the circuit of magnet 17 is completed to move the short-circuiting device 15 into engagement with the projections 16, thereby internally short-circuiting the rotor windings. This is the normal running position of the parts. The device 15 rotating with the slip-rings, there are no disadvantages arising from the sliding contacts between the slip-rings 12 and the brushes which bear thereon. The movement of the short-circuiting device 15 opens the circuit of magnet 17. Should an overload occur, the solenoid 10 is energized sufficiently strongly to raise its switch, thus closing the circuit of the solenoid 8 to trip switch 4 and cause the motor to stop. The motor cannot be started again until the bar 14 has been moved into its extreme left-hand position, during which movement the magnet 18 is energized to move the short-circuiting device 15 out of bridging position. If at any time the bar 14 is moved out of position 8, it at once, by its extension 20, closes the circuit of magnet 18 to open the internal short-circuit of the rotor windings. If desired, one set of the contacts with which the extension 20 engages to close the circuit of magnet 18 may be omitted, the two sets being provided merely for the better insuring of the movement of the device 15 out of bridging position when the arm 14 is moved to the left. There may be a handle 25 for operating the short-circuiting device 40 manually if desired.

In Figs. 2 to 6 is shown an arrangement in which the resistance 13 is varied by means of a specially constructed rheostat, this rheostat being operated in conjunction with a rotary master controller 26 of the drum type, by means of a single handle 27. A development of this drum controller is shown in Fig. 4 together with some of the controlling circuits. These controlling circuits are here shown as being supplied by a single battery 28, instead of by the separate batteries 19 and 22 of Fig. 1, the controller closing the circuits in substantially the same manner as in Fig. 1 save that the magnet 18 is energized 55 when the controller is in position 7, and the magnet 17 is energized as the controller goes from position 7 to position 8. With this arrangement, there is no necessity for the switch 21, but there is the disadvantage that the circuit of magnet 17 may not be closed sufficiently long to enable said magnet to perform its duty. It is obvious that the arrangement shown in Fig. 1 may be varied to act as the controller shown in Fig. 4 and vice versa, and that separate batteries for the

different controlling circuits may be used if desired in the arrangement of Fig. 4.

As the drum 26 is rotated by the handle 27, a chain 29 communicates motion from a sprocket wheel 30 on the shaft thereof, to a rock arm 31, upon a shaft 32. Also mounted on this shaft are arms 33 connected by links 34 to a carriage 35 mounted on rollers 36 to run on tracks 37. This carriage supports the bar 14 and is suitably insulated therefrom. On the bar 14 are mounted contact fingers 39, spring-pressed upwardly into sliding engagement with the under surfaces of contacts 40. The contacts 40 are properly connected, as by connectors 40', to the resistance 13, which is shown in Fig. 1. As the drum 26 is rotated, rectilinear movement is imparted to carriage 35 and contact fingers 39 by means of sprocket wheel 30, chain 29, rock arm 31, arms 33 and links 34. This movement cuts the resistance 13 into or out of the motor circuit in the same manner as shown in Fig. 1. Surrounding the contacts 40, contact fingers 39, carriage 35 and runway 37, is a tank containing oil in which said parts are immersed. The tank 41 is removably fastened to slotted projections 42 on the frame of the rheostat by swivel bolts 43, and is filled with oil to the "oil level" shown on the drawings.

The magnets 17 and 18 which operate the short-circuiting device 15 are identical in structure and are of the iron-clad solenoid type, the iron frame 44 of which has a projection 45 which extends into the coils. In the inner end of this projection 45 is a steel plunger 46, pressed upwardly by an adjustable spring 47. The inner surface of projection 45 has a facing 48 of non-magnetic material, through which the plunger 46 extends. The core 49 of magnet 17 has a steel plug 50 embedded in its center, which engages with the spring-pressed plunger 46 when the magnet is energized. This plunger 46 and plug 50 serves a threefold purpose: first, to take up the shock of the hammer-blow when the core 49 reaches the end of its movement; second, to allow the movement of the short-circuiting device to be completed when the magnet is energized, whatever the position of the motor shaft in its end-play, but, after the magnet has been deenergized, to return the actuating lever of said device to such a position that the sides of the groove of the short-circuiting device will not come into contact with the pin in said lever during the end-play of the shaft, the short-circuiting device being fully opened, as the case may be; and third, by reason of the higher retentivity of the parts 46 and 50, to retain the core 49, once it has been attracted, in said attracted position after the magnet 17 or 18 has been deenergized, these magnets thus having an electromagnetic actuating part and a permanently magnetic retaining part. The struc-

ture of the parts associated with magnet 18 is identical with that of those above described.

In this specification, the terms "stationary rheostat" or "stationary resistance" are used to denote a rheostat or resistance which is not mounted for rotation with the rotor. The terms "internal connection", "internal short-circuit", etc. are used to denote a connection, short-circuit or the like which is made by means carried by the rotating element of the motor and not by brushes bearing on the outer surfaces of the slip-rings.

It is obvious that many modifications may be made in the details of construction of the invention described above. All such modifications come under the broad spirit of my invention and are intended to be covered by the following claims:

What I claim as new and desire to secure by Letters Patent is:—

1. In a starter for an induction motor, the combination with said motor, of a resistance in the rotor circuit thereof, means for gradually cutting out said resistance, and means for internally short-circuiting the rotor windings effective when the resistance has been fully cut out.

2. In a starter for an induction motor, the combination with said motor, of a starting resistance connected to the rotor slip-rings thereof, means for cutting said starting resistance out of circuit, and means for connecting the slip-rings internally, said last mentioned means being effective when the starting resistance has been fully cut out.

3. In a starter for a rotor-wound induction motor, the combination with said motor, of a starting resistance connected to the rotor slip-rings thereof, manually operated means for gradually short-circuiting said starting resistance, and electrically operated means for connecting said slip-rings internally when the starting resistance has been fully cut out.

4. In a starter for an induction motor, the combination with said motor, of a rheostat in the rotor circuit thereof, means for short-circuiting the rotor windings internally, and means for operating said short-circuiting means when the rheostat is moved into its position of lowest resistance, and for opening said short-circuit when the rheostat is moved out of such position.

5. In a starter for an induction motor, the combination with said motor, of a rheostat in the rotor circuit thereof, means which in one position short-circuits the rotor windings internally, and electromagnetic means for moving said short-circuiting means into operative position when the rheostat is moved into its position of lowest resistance, and for opening said short-circuit when the rheostat is moved out of such position.

6. In a starter for a rotor-wound induction motor, the combination with said motor, of a rheostat connected to the rotor slip-rings, means for internally connecting the slip-rings, and means for operating said connecting means to connect the slip-rings when the rheostat is moved into its position of lowest resistance and for breaking such connection when the rheostat is moved into its position of highest resistance. 70

7. In a starter for a rotor-wound induction motor, the combination with said motor, of a rheostat connected to the rotor slip-rings, means for internally connecting the slip-rings, means for operating said connecting means to connect the slip-rings when the rheostat is moved into its position of lowest resistance, and for breaking such connection, if made whenever the rheostat is moved between its position of highest resistance and 85 the next position thereto.

8. In a starter for a rotor-wound induction motor, the combination with said motor, of a stationary rheostat in the rotor circuit, means which in one position short-circuits the rotor windings internally, and electromagnetic means for moving said short-circuiting means into operative position when the rheostat is moved into its position of lowest resistance and for opening said 90 short-circuit, if closed, whenever the rheostat is moved between its position of highest resistance and the next position thereto.

9. In a starter for an induction motor, the combination with said motor, of a variable 100 resistance in the rotor circuit, electromagnetically actuated means which in one position short-circuits said rotor-winding internally, and connections whereby said short-circuiting means is made operative when the 105 variable resistance has been fully cut out and said short-circuit is opened when the resistance has been fully cut in.

10. In a starter for an induction motor, the combination with said motor, of a starting resistance in the rotor circuit thereof, means for bridging internally the slip-rings of the rotor, electromagnets for moving said bridging means into and out of connection with said slip-rings respectively, and connections whereby the second of said magnets is energized as soon as the starting resistance has been begun to be cut out, and the first of said magnets energized when the starting resistance is fully cut out. 110

11. In combination, an induction motor, a magnetically operated switch for admitting current thereto, a starting resistance arranged to be included in the secondary circuit of the motor, and connections whereby 125 the operating magnet of the current-admitting switch can be energized only when the starting resistance is fully in circuit.

12. In combination, an induction motor, a magnetically operated switch for admitting 130

current thereto, a starting resistance arranged to be included in the rotor circuit of the motor, connections whereby the operating magnet of the current-admitting switch can be energized only when the starting resistance is fully in circuit, and an overload magnet for tripping the current-admitting switch when the current rises too high.

13. In combination, an induction motor, a magnetically operated switch for admitting current thereto, a starting resistance arranged to be included in the rotor circuit of the motor, means which in its operative position short-circuits the rotor-windings internally, and connections whereby the operating magnet of the current-admitting switch can be energized to close said switch only when the starting resistance is fully in circuit and the short-circuiting means is in inoperative position.

14. In combination, an induction motor, a magnetically operated switch for admitting current thereto, a starting resistance arranged to be included in the rotor circuit of the motor, means which in its operative position short-circuits the rotor windings internally, connections whereby the magnet of the current-admitting switch can be energized to close said switch only when the starting resistance is fully in circuit and the short-circuiting means is in inoperative position, and an overload magnet for tripping the current-admitting switch when the current rises too high.

35 15. In combination, an induction motor, a magnetically operated switch for admitting current thereto, a stationary starting resistance arranged to be included in the rotor circuit of the motor, means for cutting out such resistance, magnetically operated means which in its operative position short-circuits the rotor windings internally, and connections whereby the operating magnet of the current-admitting switch can be energized to close said switch only when the starting resistance is fully in circuit.

16. In combination, an induction motor, a magnetically operated switch for admitting current thereto, a stationary starting resistance arranged to be included in the rotor circuit of the motor, means for cutting out such resistance, magnetically operated means which in its operative position short-circuits the rotor windings internally, connections whereby the operating magnet of the current-admitting switch can be energized to close said switch only when the starting resistance is fully in circuit, and an overload magnet for tripping the current-admitting switch when the current rises too high.

17. In combination, an induction motor, a magnetically operated switch for admitting current thereto, a stationary starting resistance arranged to be included in the rotor circuit of the motor, means for cutting out such

resistance, magnetically operated means which in its operative position short-circuits the rotor windings internally, and connections whereby the magnet of the current-admitting switch can be energized to close said switch only when the starting resistance is fully in circuit and the short-circuiting means is in inoperative position.

18. In combination, an induction motor, a magnetically operated switch for admitting current thereto, a stationary starting resistance arranged to be included in the rotor circuit of the motor, means for cutting out such resistance, magnetically operated means which in its operative position short-circuits the rotor windings internally, connections whereby the magnet of the current-admitting switch can be energized to close said switch only when the starting resistance is fully in circuit and the short-circuiting means is in inoperative position, and an overload magnet for tripping the current-admitting switch when the current is too high.

19. In an induction motor, a primary member, a wound secondary member, means for short-circuiting said secondary member, and electromagnetic means for operating said short-circuiting means.

20. In an induction motor, a rotor having its windings connected to slip-rings, and power-operated means independent of the speed of the motor for short-circuiting said slip-rings.

21. In an induction motor, a rotor having its windings connected to slip-rings, and electrically operated means for short-circuiting said slip rings.

22. In an induction motor, a rotor having its windings connected to slip-rings, power-operated means for short-circuiting said slip-rings and a master controller for controlling the operation of said power-operated means in both directions.

23. In an induction motor, a rotor having its windings connected to slip-rings, electrically operated means for short-circuiting said slip-rings, and a master controller for said electrically operated means.

24. In combination, an induction motor, an external resistance in the secondary circuit thereof, and magnetically operated means within the motor for short-circuiting said resistance.

25. In combination, an induction motor, an external resistance in the rotor circuit thereof, means for gradually cutting out said resistance, and magnetically operated means within the motor for short-circuiting said resistance.

26. In combination, an induction motor, an external resistance in the secondary circuit thereof, means for gradually cutting out said resistance, and automatic magnetically operated means within the motor for short-circuiting said resistance.

27. In combination, a three-phase induction motor, an external resistance connected to slip-rings of the rotor thereof, and automatic magnetically operated means rotatable with said rotor for internally bridging said slip-rings.
28. In combination, a three-phase induction motor, an external resistance connected to slip-rings of the rotor thereof, and automatic electrically operated means rotatable with said rotor for internally bridging said slip-rings.
29. In combination, a three-phase induction motor, an external resistance connected to the slip-rings of the rotor thereof, means for varying said resistance, and automatic electrically operated means rotatable with said rotor for internally bridging said slip-rings.
30. In combination, an electric motor, a power-operated switch for admitting current thereto, a drum controller for controlling said switch, and a rectilinear-slide rheostat for varying the resistance in the circuit of one element of said motor, said drum controller and said rheostat being mechanically connected to operate together.
31. In combination, an electric motor, a power-operated switch for admitting current thereto, a drum controller for controlling said switch, a rectilinear-slide rheostat for varying the resistance in the circuit of one element of said motor, an operating handle, and connections whereby both rotation of the drum and movement of the rheostat are obtained by moving said handle.
32. In combination, an electric motor, a magnetically operated switch for admitting current thereto, a rectilinear-slide rheostat connected to one member of the motor, a drum controller, a single operating means mechanically connected to the rheostat and the drum controller to impart movement thereto, and electrical connections for the drum whereby the operating magnet of the current-admitting switch can be energized only when the rheostat is in position of highest resistance.
33. In combination, an induction motor, a magnetically operated switch for admitting current to the primary element thereof, a rectilinear-slide rheostat connected to the secondary element of said motor, a drum controller mechanically connected to the rheostat to impart movement thereto, and electrical connections for the drum whereby the operating magnet of the current-admitting switch can be energized only when the rheostat is in position of highest resistance.
34. In a rheostat, a plurality of sets of resistance sections, a set of contacts for each set of resistance sections, the surfaces of said contacts being downward and immersed in oil, and a relatively movable bridging member in sliding engagement with said contact surfaces and arranged to connect corresponding contacts of the various sets together.
35. In combination, a rheostat and a controlling drum arranged to be operated together, and means controlled by said controlling drum for cutting out said rheostat.
36. In combination, a rectilinear-slide rheostat and a rotatable controlling drum arranged to be operated together, and power-operated means controlled by said controlling drum for short-circuiting said rheostat.
37. In combination, an induction motor, a rheostat for the secondary circuit thereof, a controlling drum, a common operating means for said drum and rheostat, and means controlled by said drum for cutting out said rheostat.
38. In combination, a device for internally short-circuiting the rotor windings of an induction motor, and a magnet for operating said device, said magnet having a spring-pressed plunger in one of its relatively movable parts with which the other of said parts engages and acts, after the magnet is de-energized, to return the actuating mechanism of the short-circuiting device slightly to avoid friction during the end play of the rotor.
39. In combination, a device for internally short-circuiting the rotor windings of an induction motor, and a magnet for operating said device, the soft iron, relatively movable parts of said magnet having steel plugs which retain the short-circuiting device in position after the magnet is deenergized.
40. In combination, a device for internally short-circuiting the rotor windings of an induction motor, two magnets for respectively moving said device into and out of short-circuiting position, each of said magnets having a spring-pressed plunger in one of its relatively movable parts for contact with the other of said parts and acting, after the magnets are deenergized, to return partly the actuating mechanism of said short-circuiting device to avoid friction during end play of the rotor.
41. In combination, a device for internally short-circuiting the rotor windings of an induction motor, and two magnets for respectively moving said device into and out of short-circuiting position, the soft iron, relatively movable parts of said magnets having plugs of higher retentivity to retain the short-circuiting device in position after the operating magnet is deenergized.
42. In combination, a device for internally bridging the slip-rings of a rotor wound induction motor, a magnet for operating said device, and a switch in the circuit of said magnet which is automatically opened by the operation of the bridging device.

43. In combination, a device for internally bridging the slip-rings of a rotor-wound induction motor, two magnets for moving said device into and out of bridging position, and a switch in the circuit of the magnet which moves the device into bridging position which is automatically opened by such movement.

In testimony whereof I affix my signature in the presence of two witnesses.

HERBERT W. CHENEY.

Correction in Letters Patent No. 875,981.

It is hereby certified that in Letters Patent No. 875,981, granted January 7, 1908, upon the application of Herbert W. Cheney, of Norwood, Ohio, for an improvement in "Motor-Controlling Mechanism," an error appears in the printed specification requiring correction, as follows: In line 122, page 3, after the word "being," the words *fully closed or* should be inserted; and that the said Letters Patent should be read with this correction therein that the same may conform to the record of the case in the Patent Office.

Signed and sealed this 28th day of January, A. D., 1908.

[SEAL.]

C. C. BILLINGS,

Acting Commissioner of Patents.
